LUGGAGE CASE

William Wintz, Oshkosh, Wis., assignor to Oshkosh Trunks, Inc., Oshkosh, Wis., a corporation of Wisconsin

Application February 6, 1933, Serial No. 655,297

19 Claims. (Cl. 190—41)

This invention relates to portable wardrobe luggage cases of the hand carried type.

The main object and purpose of my invention is to provide an improved and novel form 5 of garment carrying fixture for the case whereby the garments may be selectively removed from the fixture without handling, lifting or in any way disturbing the other garments on the fixture.

10 Another object of my invention is to so provide the fixture that its garment supporting section extends upwardly from the case when in open position whereby the garments may hang in freely suspended relation to each other and 15 to the case to facilitate packing and unpacking of the fixture and the arranging of the garments thereon to avoid undesirable wrinkling when folded into the case.

10 A further object of my invention is to make 20 the main section of the fixture which is pivoted in the case extensible beyond the case so as to dispose the garment supporting section of the fixture when in upright position beyond the outer margin of the case, allowing the garments to 25 hang freely their full length without encountering any obstructions.

10 A further object of my invention is to provide 30 a fixture so constructed and arranged that garment hangers of the type usually employed in wardrobe trunks may be used with the fixture for supporting garments thereon, thereby giving the case the same packing conveniences as a 35 wardrobe trunk.

10 A further object of my invention is to provide 35 locking members for holding the garment hangers positively in place upon the trolleys of the fixture.

10 A further object of my invention is to so 40 arrange these locking members that when in open position they provide forward extensions for the trolley surfaces to facilitate spreading the garment hangers for the selective removal of the garments from the fixture.

10 A further object of my invention is to provide 45 the trolleys in fixed angular relation to the portion of the fixture which supports them so that the trolleys with hangers thereon will be raised to the desired accessible portions above and at the front of the case when opening the fixture for the packing and unpacking of the same.

10 The invention consists further in the matters 50 hereinafter described and claimed.

In the accompanying drawings:

55 Fig. 1 is a perspective view of a luggage case

equipped with a garment carrying fixture of my invention, the case being shown in open position and the fixture in garment hanging position;

Fig. 2 is a top plan view of the structure shown in Fig. 1, the lid of the case being shown in horizontal section and the garment carrying fixture in collapsed position over the body of the case; 5

Fig. 3 is a vertical sectional view taken on line 3—3 of Fig. 2, the garment carrying fixture being shown in garment hanging position in heavy 10 lines and in collapsed position in the lid or cover of the case in lighter lines;

Fig. 4 is a sectional view taken through the fixture on line 4—4 of Fig. 2; and

Fig. 5 is a vertical sectional view taken on line 15 5—5 of Fig. 1.

As shown in the drawings, the case to which my invention is applicable is of the box type having hingedly connected body and lid or cover sections 1, 2. The hinge connection 3 between the 20 sections is at the rear of the case, being along the upper edge of the rear wall 4 of the body section as shown in Fig. 3. The lid or cover 2 when closed fits against the upper edge of the body section 1 and is releasably secured thereto by latch and bolt means on the front walls of the cover and body sections, respectively, as in devices of this general character. In Fig. 1, 5, 6 indicate the parts of the latch and bolt means on the front wall 7 of the body section 1. 25

The garment carrying fixture of my invention fits within the case when in collapsed position and in the particular form of construction shown in the drawings is received in the lid or cover section 2. Said fixture comprises a main section 8 and a garment supporting section 9. The main section 8 is pivoted at its inner end in the cover 2 adjacent the hinge connection between the cover and the body of the case. The garment supporting section 9 is pivoted to the outer or free end of the main section 8 and is swingable from a position in overlapping relation with the main section into a raised position extending above the main section when the latter is in lowered position over the top of the body of the case as 40 shown in Figs. 1 and 3. 45

The section 9 is provided at its upper or free end with trolleys 10 to support garment hangers 11. The latter are of the type employed in wardrobe trunks and have hooks 12 or other means at their opposite ends to engage the trolleys for suspending the hangers between them as shown in Figs. 1 and 5. Hangers of both the single bar and combined bar and coat carrying type 50 may be employed for supporting coats and suits, 55

as well as dresses. The latter are draped over the cross-bars of the hangers when applied thereto as usual with hangers of this character. (See Fig. 3.)

5 The garment carrying fixture is provided with a cross-bar 13 adjacent the point of connection of the section 8 with the section 9 so that the portions of the garments hanging from the trolleys 10 may fold over said bar when swinging the fixture 10 into the case about its pivotal connection therewith. Thus, the garments hung on the fixture when packing the same may automatically fold over the bar to fit within the confines of the case when the fixture is collapsed and swung into the 15 lid. In the particular structure shown in the drawings, the bar 13 is secured to the section 9 adjacent its pivotal section with the section 8, thus positioning the bar uppermost when the fixture is collapsed and swung into the lid. With 20 the trolleys at the opposite end of the section 9, the trolleys will be at the lower end of said section when the fixture is collapsed and swung into the lid, as shown by the lighter lines in Fig. 3. Bar 13 is rounded in cross-section to avoid creasing the garments when folded thereover. Guards 25 in the form of flat discs 14, 14 are at the opposite ends of the bar to prevent the garments from sliding off of the same.

For holding the hangers 11 on the trolleys 10, 30 I provide latch members 15 pivoted to the trolleys and swingable into closed positions over the same as shown in Figs. 1, 3 and 5. The latch members, when in closed positions, contact with a cross-bar 16 at the inner end of the main section 8 when the fixture is collapsed and swung into the 35 lid as shown in Fig. 3. Thus the hangers are held positively in place on the trolleys 10 and cannot lose their connection therewith when the fixture is in the lid.

40 The trolleys 10 are made wide enough to support the desired number of hangers 11 in side by side relation. The latch members 15 are pivoted at 17 to the outer ends of the trolleys so that when the latch members are swung into open 45 positions as shown in Fig. 3, they project outwardly beyond the upper end of the section 9 to continue the support as provided by the trolleys for the garment hangers. This lengthens the trolley support and enables the hangers while on 50 the trolleys to be spread apart so that any of the garments may be readily and easily lifted from the trolleys without disturbing or lifting or in any way handling the other garments thereon. Thus, the garments on the trolleys may be selectively 55 removed therefrom without regard to the order in which they are packed on the fixture. Manifestly, the particular garment desired may be lifted from the fixture without the necessity of first removing all of the garments in advance of 60 the selected one as required in those luggage cases where the garments lie in piled or superimposed relation when the carrying fixture is positioned for access. The feature of being able to remove any selected garment from the trolleys 65 without disturbing the other garments thereon is an important and advantageous one of my invention. It embodies in a luggage case of the hand carried type one of the advantages of a wardrobe trunk as to the convenience of removing the packed garments.

70 The trolleys 10 and the latch members 15 are provided with lugs 18 and 19, respectively, forming stops for the hangers at the opposite ends of the supporting surfaces provided therefor. These 75 stops also enable the latch members to have a

releasable snap connection with the trolleys when the latch members are swung into closed position as shown in Fig. 1. For this purpose the lugs may be provided with interfitting parts, such as bosses and recesses, respectively, to hold the latch members against accidental opening when the section 9 is in raised position for packing and unpacking. The latch members may have side lugs 20 to facilitate swinging them into and out of closed positions. These lugs contact with the bar 16 or other means provided on the main section 8 for holding the latch members closed when the fixture is collapsed and in its retained position in the case.

75 The main section 8 is extensible to so dispose the section 9 when in its raised position that the garments may hang freely outside of the case when packing and unpacking the fixture. In the particular form of my invention as shown in the drawings, the section 8 is extensible beyond the 20 front wall 7 of the case and is supported in its lower position by resting on the upper edge of said wall. The section 9 is thus disposed exteriorly of said wall when the section 8 is fully extended, as shown in Figs. 1 and 3. With the 25 trolleys 10 at the upper end of the section 9, when the latter is in its raised or garment supporting position, the garments may hang freely from the hangers 11 on the trolleys with the lower or tail ends of the garments out of contact 30 with the floor when the case is set on a table, chair or other elevated support. Moreover, with the trolleys 10 projecting forwardly beyond the front side of the section 9 when raised, the garments hang free of the body of the case and are 35 unobstructed thereby on being applied to or removed from the trolleys. With the trolleys in fixed angular relation to the section 9, the trolleys are brought into their garment hanging positions in the mere act of raising the section to its garment supporting position above the body of the 40 case.

45 It will be observed from Fig. 3, that with the latch members 15 pivoted to the ends of the trolleys 10 and shaped as shown, the latch members 45 will be at a lower level than the trolleys when in fully extended positions. Thus any hangers 11 on the latch members will be automatically returned to the trolleys on swinging the latch members into their closed positions over the 50 trolleys as indicated in dotted lines in Fig. 3. This avoids the necessity of manually lifting the individual hangers on the latch members back onto the trolleys when positioning the parts for closing the latch members.

55 The section 8 may be in the form of a metal frame in which event its side members 21, 22, as shown in the drawings, will be telescopically or slidably connected as by sleeves 23, 23. The latter 60 may be fixed to the innermost of the side members 22, the outermost members 21 having projections 24 forming stops to limit the extensibility of the section. The cross-bar 16 at the inner end of the section 8 may be integrally connected with its side members 21, the whole being formed from a single metal bar. The side members 22 are 65 connected between the sleeves by a cross-member 25 which serves to brace the frame and also to provide a support for the section 9 and its garments when swung into folded relation with the section 8 as shown in Fig. 2. Side members 21 of the section 8 are provided adjacent their inner ends with pivotally attached U-shaped or other connectors 26 adapted to be inserted into brackets 70 75

27 in the cover 2 of the case for pivotally connecting the fixture in the case.

The section 9 may also be in metal frame form in which case its side members 28, 28 are pivoted at 29, 29 to the outer or free ends of the side members 22 of the section 8. This pivotal connection is disposed adjacent one end of the section 9 so that cross-bar 13 may be connected with the side members 28 and serve as a support for the folded portions of the garments as heretofore stated. The trolleys 10 are preferably stamped from sheet metal and are riveted or otherwise secured to the upper or free ends of the side members 28, said trolleys being connected across the frame by a cross-bar 39. This bar is on the inner side of the section when in raised position and also serves as a limiting stop for the garments when packed on the frame.

The section 9 may be held in its upright or raised position by links 31, 31 on opposite sides of the frame. These links are pivoted at 32 to the side members 22 of the main frame 8 and have longitudinal slots 33 engaging pins 34 on the outer sides of the side members 28 of the section 9 to limit the extent to which the section 9 may be raised and also to cause the links 31 to swing down into collapsed relation with the sections 8 and 9 when the fixture is folded and collapsed for swinging into the cover of the case as shown in Fig. 2.

For holding the fixture in the cover of the case I may provide any desired form of holding means. In the drawings, I have shown a flexible curtain 35 attached to the upper or outer end of the cover 2 and swingable over the outer side of the fixture when in the cover. This curtain is wide enough to practically cover the garments on the fixture and may be made long enough to extend into the body of the case adjacent its rear wall 4 as shown in Fig. 3. The curtain is provided adjacent its free end with a metal rod 36, the ends of which extend beyond the sides of the curtain and are engageable with any one of a number of notches formed between teeth 37 on the trolley members 10 as shown in the drawings. These teeth are disposed on the outer side of the section 9 when the fixture is in the cover of the case so as to be engaged by the rod of the curtain.

To collapse the fixture to fit within the lid 2 of the case, the section 9 is first swung down upon the section 8, whereupon section 8 is contracted and swung into the lid on its pivotal connection therewith. The curtain is then closed over the outer side of the fixture and the garments thereon and locked in place, thus confining the fixture and its garments within the lid. The body of the case may be partitioned as desired, and is packed and used without interference by the garments on the fixture within the lid.

A case equipped with a garment carrying fixture of my invention has practically the same conveniences as a regular wardrobe trunk insofar as applying garments to and removing them from the fixture. This is of considerable advantage as the public are familiar with the way to pack a standard wardrobe trunk and are well satisfied with its convenience. With the garment supporting section 9 of the fixture extensible to a raised position, the fixture may be packed and unpacked in a manner similar to that of packing and unpacking the wardrobe section of a wardrobe trunk. The trolleys 10 are directly in front of the user and are high enough for the hangers thereon to be easily and conveniently reached. Moreover, with the supporting fixture 9 in raised

position, a vertical support is provided for the garments permitting them to hang freely for selective removal and arrangement, avoiding wrinkling when folded and held in the lid of the case.

Another advantage is that garment hangers of the type usually employed in wardrobe trunks may be used with the fixture and thus render the case usable for both men and women without requiring special fixtures as heretofore. This universality in packing in a luggage case of the hand carried type is an important advantage both from a commercial and a user's standpoint.

The details of construction and arrangement of parts shown and described may be variously changed and modified without departing from the spirit and scope of my invention, except as pointed out in the appended claims.

I claim as my invention:

1. A hand carried luggage case, comprising a body and a cover hinged together, a garment carrying fixture having a main section and a garment supporting section, said main section having its inner end pivoted in the cover adjacent the hinged connection between the body and the cover and swingable into and out of a lowered position over the body of the case, said main section and said case body having provision for mutual engagement to provide a support for said main section when in a lowered position over the body of the case, said garment supporting section being pivoted to the main section adjacent its free end and swingable from a folded position with respect to the main section to a position extending above the main section when the latter is in lowered position over the body of the case, means for holding the supporting section in its raised position, trolleys for garment hangers on the supporting section adjacent its outer end, latch members pivoted to the trolleys and swingable over the same for holding the hangers on the trolleys, and means carried by the main section for contact with the latch members when the main and supporting sections are in folded relation in the cover of the case for holding the latch members closed.

2. A hand carried luggage case, comprising a body and a cover hinged together, a garment carrying fixture having a main section and a garment supporting section, said main section being pivoted at its inner end in the cover adjacent the hinged connection between the body and the cover and swingable into and out of a lowered position over the body of the case, said main section and said case body having provision for mutual engagement to provide a support for said main section when in a lowered position over the body of the case, said garment supporting section being pivoted to the main section adjacent its free end and swingable from a folded position with respect to the main section to a raised position above the same, means for holding the supporting section in its raised position, and means carried by the case for holding the fixture in the cover when the fixture is collapsed and swung into the cover.

3. A hand carried luggage case, comprising a body and a cover hinged together, a garment carrying fixture having a main section and a garment supporting section, said main section having its inner end pivoted in the cover adjacent the hinged connection of the cover with the body of the case and swingable into and out of a lowered position over the body of the case, said main section and said case body having provision for mutual engagement to provide a sup-

port for said main section when in a lowered position over the body of the case, said garment supporting section being pivoted to the main section adjacent its outer end and swingable from a folded position with respect to the main section to a raised position extending above the same, means for holding the supporting section in its raised position, a curtain carried by the cover and swingable over the outer side of the fixture when in the cover, and interengageable means on the curtain and the fixture for holding the curtain over the fixture and the latter in the cover.

4. A hand carried luggage case, comprising a body and a cover hinged together at the rear of the case, a garment carrying fixture having a main section and a garment supporting section, said main section being pivoted at its inner end in the cover adjacent the hinged connection of the cover with the body of the case and swingable into and out of a lowered position over the body of the case, said main section and said case body having provision for mutual engagement to provide a support for said main section when in a lowered position over the body of the case, said garment supporting section being pivoted to the main section adjacent its free end and swingable to a raised position above the main section when the latter is in its lowered position over the body of the case, trolleys for garment hangers and a cross-bar for the garments thereon at the opposite ends of said support section, links for holding the supporting section in its raised position and swingable therewith into folded relation with the main section, and latch members pivoted to the trolleys and swingable into closed positions thereover for holding the hangers thereon, said latch members being at a lower level than the trolleys when in open positions and serving to return any hangers thereon to the trolleys when moved into their closed positions.

5. A hand carried luggage case, comprising a hingedly connected body and cover, a garment carrying fixture having a main section and a garment supporting section, said main section having its inner end pivoted in the cover adjacent the hinged connection between the cover and the body and swingable from the cover into and out of a lowered position over the body of the case, said main section and said case body having provision for mutual engagement to provide a support for said main section when in a lowered position over the body of the case, said supporting section being pivoted to the main section adjacent its free end and swingable from a folded position with respect to the main section to a raised position extending above the main section when the latter is in lowered position over the body of the case, means for holding the supporting section in its raised position, and trolleys for garment hangers on the supporting section adjacent its free end, whereby garments may be attached to and be removed from the supporting section when in its raised position, said trolleys being substantially normal to the supporting section and extending outwardly therefrom when the supporting section is in its raised position, said main section disposing the garment supporting section when in its raised position adjacent the front wall of the case opposite the hinged connection between the cover and the body of the case, whereby the garments supported by the trolleys may hang outside of the case exteriorly of said front wall.

6. A hand carried luggage case, comprising a

hingedly connected body and cover, a garment carrying fixture having a main section and a garment supporting section, said main section having its inner end pivoted in the cover adjacent the hinged connection between the cover and the body and swingable from the cover into and out of a lowered position over the body of the case, said main section and said case body having provision for mutual engagement to provide a support for said main section when in a lowered position over the body of the case, said supporting section being pivoted to the main section adjacent its free end and swingable from a folded position with respect to the main section to a raised position extending above the main section when the latter is in lowered position over the body of the case, means for holding the supporting section in its raised position, trolleys for garment hangers on the supporting section adjacent its free end, whereby garments may be attached to and removed from the supporting section when in its raised position, said trolleys being substantially normal to the supporting section and extending outwardly therefrom when the supporting section is in its raised position, said main section disposing the garment supporting section when in its raised position adjacent the front wall of the case opposite the hinged connection between the body and the cover of the case, whereby garments supported by the trolleys may hang outside of the case exteriorly of said front wall, and latch members connected to the trolleys and swingable over the same for locking the hangers thereon, said latch members when open forming continuations for the trolleys on the outer side of the supporting section.

7. A hand carried luggage case, comprising a hingedly connected body and cover, a garment carrying fixture having a main section and a garment supporting section, said main section being pivoted at its inner end in the cover adjacent the hinged connection between the cover and the body and swingable from the cover into and out of a lowered position over the body of the case, said main section and said case body having provision for mutual engagement to provide a support for said main section when in a lowered position over the body of the case, said supporting section being pivoted to the main section adjacent its free end and swingable to a raised position above the main section when the latter is in lowered position over the body of the case, means for holding the supporting section in its raised position, means on the supporting section adjacent its free end providing teeth on the inner side of the supporting section and trolleys for garment hangers extending outwardly from the supporting section on its outer side, and a curtain secured to the cover and swingable over the outer side of the fixture when in the cover, and means carried by the curtain and engageable with the teeth on the supporting section for holding the curtain over the fixture and the latter in the cover.

8. A hand carried luggage case, comprising a hingedly connected body and cover, a garment carrying fixture having a main section and a garment supporting section, said main section being pivoted at its inner end in the cover adjacent the hinged connection between the cover and the body and swingable from the cover into and out of a lowered position over the body of the case, said supporting section being pivoted to the main section adjacent its free end and swingable to a position above the main section when the latter is in lowered position over the body of the case.

the case, means for holding the supporting section in its raised position, trolleys for garment hangers on the supporting section adjacent its free end, said trolleys being substantially normal to the supporting section and extending outwardly therefrom when the supporting section is in raised position, and a cross-bar carried by the fixture adjacent the pivotal connection between the main and the supporting sections for folding thereover of the garments on the supporting section when the fixture is collapsed and swung into the cover, said main section being extensible, when in lowered position, whereby the supporting section when raised may be disposed exterior of the body of the case opposite its hinged connection with the cover, said main section and said case body having provision for mutual engagement to provide a support for said main section when in lowered position over the body of the case.

9. A hand carried luggage case, comprising a hingedly connected body and a cover, a garment carrying frame having a main section and a garment supporting section, said main section having its inner end pivoted in the case adjacent the hinged connection between the body and the cover and swingable into and out of a lowered position over the body of the case and said main section and said case body having provision for mutual engagement to provide a support for said main section when in lowered position over the body of the case, said supporting section being pivoted to the main section adjacent its free end and swingable to a raised position extending above the main section when the latter is in lowered position, trolleys for garment hangers on the supporting section adjacent its free end, said main section supporting the supporting section in its raised position adjacent the front wall of the case opposite the hinged connection between the body and the cover, and means for holding the supporting section in its raised position.

10. A hand carried luggage case, comprising a hingedly connected body and a cover, a garment carrying frame having a main section and a garment supporting section, said main section having its inner end pivoted in the case adjacent the hinged connection between the body and the cover and swingable into and out of a lowered position over the body of the case, said main section and said case body having provision for mutual engagement to provide a support for said main section when in a lowered position over the body of the case, said supporting section being pivoted to the main section adjacent its free end and swingable to a raised position extending above the main section when in lowered position, trolleys for garment hangers on the supporting section adjacent its free end, said main section supporting the supporting section in its raised position adjacent the front wall of the case opposite the hinged connection between the body and the cover, said trolleys extending outwardly from the supporting section when in its raised position whereby the garments supported by the trolleys may hang exteriorly of the case on the outer side of said front wall, and means for holding the supporting section in its raised position.

11. A hand carried luggage case, comprising a hingedly connected body and a cover, a garment carrying fixture having a main section and a garment supporting section, said main section having its inner end pivoted in the case and swingable into and out of a lowered position over the body of the case, said main section and said case

body having provision for mutual engagement to provide a support for said main section when in a lowered position over the body of the case, said garment supporting section being connected with the main section adjacent its free end and movable to a position extending upwardly from the main section when the latter is in a lowered position over the body of the case, means for holding the garment supporting section in its raised position, and means carried by the supporting section whereby garments may be attached to and be removed from the supporting section when in its raised position.

12. A hand carried luggage case, comprising a hingedly connected body and a cover, a garment carrying fixture having a main section and a garment supporting section, said main section having its inner end pivoted in the case and swingable into and out of a lowered position over the body of the case, said main section and said case body having provision for mutual engagement to provide a support for said main section when in a lowered position over the body of the case, said garment supporting section being pivoted to the main section adjacent its free end and swingable into and out of a raised position extending above the main section from a collapsed position lying alongside the main section when the latter is in a lowered position over the body of the case, means for holding the garment supporting section in its raised position, means carried by the garment supporting section whereby garments may be attached to and be removed from the supporting section when in its raised position, and a cross-bar carried by the fixture adjacent the pivotal connection between the sections whereby the garments on the supporting section may fold over the cross-bar when the fixture with its sections in collapsed relation is swung upwardly from its lowered position.

13. A hand carried luggage case, comprising a hingedly connected body and a cover, a garment carrying fixture having a main section and a garment supporting section, said main section having its inner end pivoted in the case and swingable into and out of a lowered position over the body of the case, said main section and said case body having provision for mutual engagement to provide a support for said main section when in a lowered position over the body of the case, said garment supporting section being connected with the main section and movable from a folded position with respect to the main section to a raised position extending above the main section when the latter is in a lowered position over the body of the case, trolleys for garment hangers on the supporting section adjacent its free end, said trolleys being extensible whereby the supporting lengths of the trolleys may be increased so that the hangers may be spread while on the trolleys to facilitate their selective removal from the trolleys when the supporting section is in its raised position, and means for holding the supporting section in its raised position.

14. A hand carried luggage case, comprising a hingedly connected body and a cover, a garment carrying fixture having a main section and a garment supporting section, said main section having its inner end pivoted in the case and swingable into and out of a lowered position over the body of the case, said main section and said case body having provision for mutual engagement to provide a support for said main section when in a lowered position over the body of the case, said garment supporting section being con-

nected with the main section adjacent its free end and movable to a raised position extending above the main section when the latter is in a lowered position over the body of the case, means 5 for holding the supporting section in its raised position, trolleys for garment hangers on the supporting section, and latch members carried by the trolleys for holding the hangers thereon, said latch members providing extensions for the 10 trolleys when in open position, said main section disposing the garment supporting section when in its raised position adjacent the front wall of the case opposite the hinged connection between the cover and the body, whereby the garments supported by the trolleys may hang outside of the case exteriorly of said front wall.

15. A hand carried luggage case, comprising a hingedly connected body and a cover, a garment carrying fixture having a main section and a 20 garment supporting section, said main section having its inner end pivoted in the case and being extensible whereby the main section may be swung to a lowered extended position over the body of the case and supported in the latter position by the body of the case, said garment supporting section being pivoted to the main section and swingable into and out of a raised position extending above the main section from a folded position with respect to the main section when 25 the latter is in a lowered position over the body of the case, means for holding the supporting section in its raised position, and means carried by the supporting section whereby garments may be attached thereto, said supporting section being connected with the main section adjacent its free end whereby the garments on the supporting section may hang exteriorly of the case when the main section is in its lowered extended position and the supporting section is in its raised 40 position.

16. A hand carried luggage case, comprising a hingedly connected body and a cover, a garment carrying fixture having a main section and a garment supporting section, said main section having extensible side members and pivoted at 45 its inner end in the case adjacent the hinged connection between the body and the cover whereby the main section may be swung to a lowered position over the body of the case and be extended to be supported by and project beyond the wall of the case body opposite the hinged connection of the body with the cover, said garment supporting section being pivoted to the main section and swingable to a raised position 50 extending above the main section when the latter is in a lowered position over the body of the case, trolleys for garment hangers at the free end of the supporting section, and means for holding the supporting section in its raised position, said supporting section being connected to the outer ends of the extensible side members of the main section whereby the supporting section may stand exteriorly of said body wall when the main section is in its lowered extended position and the supporting section is in its raised 65 position.

17. In a hand luggage case, a main section, a cover hingedly connected thereto for swinging movement from a closed position to an upright 70 open position, a garment carrying unit comprising two hingedly connected elements, hanger supports on one of said elements, individual garment hangers readily detachably carried by said hanger supports, means to hingedly mount the 75 other of said elements in the case for swinging

movement about an axis near the hinged connection between the cover and the main section, means to support said last mentioned element against dropping down into the main section when the case is open so that the first designated 5 element is free to be swung from a position in line with the second designated element over the main section to an upright position at which garments carried by the individual hangers may hang down over the front of the main section, 10 and means to limit movement apart of said elements to define said upright position of the first designated element.

18. In a hand luggage case, a main section, a cover hingedly connected thereto for swinging movement from a closed position to an upright open position, a garment carrying unit comprising two hingedly connected elements, hanger supports on one of said elements, individual garment hangers readily detachably carried by said hanger supports, means to hingedly mount the other of said elements in the case for swinging movement about an axis near the hinged connection between the cover and the main section, means to support said last mentioned element against dropping down into the main section when the case is open so that the first designated element is free to be swung from a position in line with the second designated element over the main section to an upright position at which garments carried by the individual hangers may hang down over the front of the main section, and means to limit the movement of said elements about their hinged connection to substantially ninety degrees whereby said first designated section may be held in said upright position when the case is open.

19. In a hand luggage case, a main section having front and rear walls, a cover section hingedly connected to the rear wall for movement from a closed position to an upright open position, a garment carrying unit comprising a pair of opposite arms, means at one end of the arms to hingedly mount the same in one section adjacent its hinged connection with the other section for swinging about an axis adjacent and parallel to the rear wall of the main section from a position disposed over the open top of the main section when the case is open to an upright position, means to support the arms against dropping down into the main section when the case is open, a pair of spaced side members each hingedly connected to the free end of one of said arms to be movable from a collapsed position in line with the arms to an upright position substantially parallel with the open cover section while the arms remain in their positions disposed over the open top of the main section, means to limit movement of the side members away from the arms to define the upright positions of the side members at which their outer ends are substantially above the front of the main section, a hanger support at the outer free end of each side member, a garment hanger engageable at its end portions with said hanger supports so that garments carried by said hanger may hang down past the front wall of the main section, a garment supporting member rigidly connecting the side members adjacent their hinged connection with the supporting arms and over which such garments are foldable, and means to rigidly tie the outer ends of the side members together.
